UNITED STATES PATENT OFFICE.

EDWARD B. NOWOSIELSKI, OF BLOOMFIELD, NEW JERSEY, ASSIGNOR TO SPLITDORF ELECTRICAL COMPANY, OF NEWARK, NEW JERSEY.

MAGNETO-ELECTRIC GENERATOR.

Application filed September 28, 1926. Serial No. 138,144.

This invention relates to an ignition apparatus suitable for firing the charges in an internal combustion engine. It has been found that the power of an internal combustion engine is increased by having a plurality of sparks to fire the charges in each cylinder but this practice has not been generally followed, on account of the increased cost, however for certain classes of work 10 two or more sparks have been utilized.

It is the principal object of my invention to provide an ignition device which is capable of producing a plurality of sparks for the purpose of increasing the power of the 15 engine and securing a greater margin of operative safety.

I have preferred to incorporate my invention into a magneto electric generator, and the invention will be best understood 20 by reference to the drawings, in which

Figure 1 is a longitudinal vertical sectional view through the magneto.

Figure 2 is an end view of the breaker end of the magneto but with some of the 25 details in connection with the distributor arranged somewhat differently than in Figure 1.

Figure 3, is a view from the driving end of the magneto with the end plate removed, 30 while

Figure 4, is a diagram of the preferred form of circuit arrangement.

Referring now to details wherein like numbers refer to corresponding parts in the 35 various views, 1 is a frame, to which is attached the driving end plate 2, and a breaker end plate 3. Within the frame 1, is rotatably mounted on the usual ball bearing 4, an armature 5, having a driving shaft end 40 6. The armature 5, has a low tension winding 7, one end of which is grounded to the armature and the other end is carried out by means of a stud 8, to the stationary contact 9, through the contact member 38, 45 which is attached to the member 40, carrying the contact 9. The member 40 is insulated from the frame, by an insulator 41. These parts are well known, and therefore need no detailed explanation. Cooperating

with the contact 9, is a breaker arm 10 operated by the usual cam 11 for controlling the current in the armature winding 7. The circuit breaker arm 10 is carried on a stud 39. Across the top of the frame 1, is a pair of magnetic members 12 and 13, which are preferably made of good magnetic material. The members 12 and 13 are somewhat shorter than the distance between the limbs of the magnet or magnets 14, which are associated with pole pieces 15 between 50 which the armature 5 rotates, so that there is little or no magnetic leakage from one limb of the magnet through the members 12 and 13, to the other limb of the magnet. 55

While Figure 1 shows two magnets, it is 60 to be understood that in the specification and claims where a magnet is referred to, it means either a single or a plurality of magnets, so arranged as to give the effect of one single magnet. 65

Positioned on each of the members 12 and 13 is a coil structure including core members 16, the ends of which rest on the extremities of each of the members 12 and 13. Each of the core members 16 carries 70 a coil 17, which is preferably made up of a primary winding 18, and secondary winding 19. The cores 16 are held to the members 12 and 13, by clamps 20, preferably of non-magnetic material. The clamps 20 are 75 held in place by studs 21 and nuts 22, which are positioned on opposite ends of the coil structure. The secondary winding of each of the coils is brought out through suitable connectors, and carried to the distributor. 80 As clearly shown in Figure 1, the distributor in general comprises a block 23, in which is fastened the necessary number of terminals, to which cables 24 are attached, and held in position by a cover 25. The cover 25 is held to the block 23, by studs 26 and nuts 27, which are prevented from coming off due to vibration, by means of a wire 28 threaded through holes 29, in the ends of the 85 studs 26.

The high tension current from one of the coils is brought to a distributing finger 30, and the high tension current from the other

stationary coil is brought to the distributing finger 31, the fingers 30 and 31 being carried by a rotating member 32 of suitable insulating material, carried by the distributor gear 33, which in turn is driven by a pinion 34 on the cam end of the armature 5.

The various details entering into the distributing features of the machine, are not further described in detail as my invention 10 relates, particularly to the generating features, which includes the main generating winding 7, and the auxiliary windings, 18 and 19.

The operation of my magneto electric generator will be readily understood by the following brief description: As the armature 5 and winding 7 thereon is operated the current is generated in the winding 7 in the usual way, due to the passage of magnetic flux through the armature 5. This current is controlled by the circuit breaker actuated by the cam 11, and at the proper instant in the cycle of operation, the circuit breaker opens when the current from the 20 winding 7 is a maximum and this energy is discharged through the primary windings 18 of the stationary coils carried on the cores 16, and simultaneously with this operation, sparking current is generated in the 25 secondary windings 19, and distributed to the respective spark plugs 35 in the engine cylinders. It may be noted in passing that the usual condenser 36, which is shown as carried by the armature 5 is connected across 30 the circuit breaker points to prevent sparking thereat, also a switch contact 37 is provided for shortcircuiting the winding 7, when it is desired to stop the engine.

It will be noted from the diagram of Figure 4, that the windings 18 are connected 40 in series with the primary winding 7, which is the preferred way of operating the generator, but the windings 18 themselves may be connected in parallel.

I have found that by utilizing the entire 45 space on the armature 5 for a single low tension winding and arranging the stationary coils in the manner shown and described, that I can obtain results far better than in 50 any other manner, so that two hot sparks may be provided at most extremely low speed of the armature 5. I have thus obtained a generator which will deliver two simultaneous sparks to each engine cylinder 55 without the generation of one spark interfering with the generation of the other spark.

In the drawing I have shown a two spark machine for a six cylinder engine since the 60 distributor block shown in Fig. 2, provides for twelve cables or a pair for each of six cylinders, but it is to be understood that the machine may readily be constructed for a two spark four cylinder, or two spark eight 65 cylinder, engine, etc.

It will be also apparent that numerous changes may be made in the details for carrying my invention into practice and the claims are directed to cover the invention in its broadest aspect.

Having thus described my invention, what I claim is:

1. A magneto electric generator comprising, a frame, a permanent magnet and pole pieces therefor, carried by the frame, an armature mounted within the frame, for rotary movement between said pole pieces, a plurality of magnetic members carried on the top of said frame, a coil core structure supported on each of said magnetic members, at least one winding on each of said coil core structures, a winding on said armature connected to the windings on said coil core structures and a circuit breaker actuated on rotation of the armature for controlling the action of all of said windings. 80

2. A magneto electric generator comprising a frame, a permanent magnet and pole pieces therefor carried by the frame, an armature mounted within the frame, for rotary movement between said pole pieces, a plurality of magnetic members carried on the top of said frame, at right angles to the axis of the armature and being in length, appreciably less than the distance between the limbs of the magnet, a coil core structure supported on each of said magnetic members, at least one winding on each of said coil core structures, a winding on said armature, connected to the windings on said coil core structures, and a circuit breaker actuated on rotation of the armature for controlling the action of all of said windings. 90

3. A magneto electric generator comprising a frame, a permanent magnet and pole pieces therefor carried by the frame, an armature mounted within the frame, for rotary movement between said pole pieces, a plurality of magnetic members carried on the top of said frame, a coil core structure supported on each of said magnetic members, a primary and a secondary winding on each of said coil core structures a single low tension winding on said armature connected to the primary windings on said coil core structures and a circuit breaker actuated on rotation of the armature for controlling the discharge, of the winding on the armature, into the primary windings on said coil core structures. 110

4. A magneto electric generator comprising a frame, a permanent magnet and pole pieces therefor, carried by the frame, an armature mounted within the frame for rotary movement between said pole pieces, a plurality of magnetic members carried on the top of said frame, a coil core structure supported on each of said magnetic members, a primary and a secondary winding on each of said coil core structures, a single low 125

tension winding on said armature connected in series with the primary windings on said coil core structures and a circuit breaker connecting the winding on the armature 5 for controlling the discharge of said armature winding into said coil primary windings.

5. A magneto electric generator comprising a frame, a permanent magnet and pole 10 pieces therefor carried by the frame, an armature mounted within the frame for rotary movement between said pole pieces, a pair of bar shaped magnetic members extending across the top of the frame at right 15 angles to the axis of the armature, a pair of coils each having a core with the ends resting on the extremities of its respective bar shaped member, at least one winding on each of said coil core structures, a winding on 20 said armature connected to the windings on said coil core structures and a circuit breaker actuated on rotation of the armature for controlling the action of all of said windings.

25. 6. A magneto electric generator comprising a frame, a permanent magnet and pole pieces therefor, carried by the frame, an armature mounted within the frame for rotary movement between said pole pieces, a 30 pair of bar shaped magnetic members extending across the top of the frame at right angles to the axis of the armature, a pair of coils each having a core with its ends resting on the extremities of its respective 35 bar shaped member, primary and secondary windings on each of said coil cores, a winding on said armature connected with the primary windings of said coils carried on the frame and a circuit breaker for controlling 40 the discharge of the armature winding into the said coil primaries.

7. A two spark electric generator comprising, a frame carrying a rotating armature having a low tension winding thereon 45 controlled by a circuit breaker, means for passing magnetic flux through said armature, a plurality of stationary coils carried by the frame, each having a complete magnetic circuit independent of the magnetic 50 circuit through the armature and each of said coils having a winding connected so as to be excited by the winding on the armature according to the functioning of the circuit breaker.

55. 8. A two spark electric generator comprising, a frame carrying a rotating armature having a low tension winding thereon controlled by a circuit breaker, means for passing magnetic flux through said armature, a 60 pair of stationary coil structures carried by the frame and each having a magnetic circuit independent of the armature magnetic circuit, each of said coil structures having primary and secondary windings thereon, 65 said primary windings being connected so

as to be excited by the winding on the armature according to the functioning of the circuit breaker.

9. A two spark electric generator comprising, a frame carrying a rotating armature 70 having a low tension winding thereon controlled by a circuit breaker, means for passing magnetic flux through said armature, a plurality of stationary coil structures carried by the frame, each coil structure having 75 a complete magnetic circuit independent of the magnetic circuit through the armature, each of said coil structures having primary and secondary windings, said primary windings being connected in series 80 with the winding on the armature, a circuit breaker connected across said armature winding and means for actuating the circuit breaker on rotation of the armature.

10. A magneto electric generator comprising, a frame carrying pole pieces and having a horseshoe magnet fitting thereon, an armature rotatably mounted between said pole pieces and having a single low tension winding 85 and a circuit breaker for controlling said winding, a pair of independently constructed coil structures each including separate magnetic circuits mounted on the frame within the arch of the magnet, each of said coil structures having primary and secondary 90 windings, the primaries being connected to the armature winding and the secondaries 95 to a distributing device.

11. An ignition generator for delivering 100 two sparks simultaneously, including a rotating armature and winding thereon, with means for sending magnetic flux therethrough and a pair of stationary coil structures each having a magnetic circuit independent of the armature, said stationary 105 coil structures each having at least one winding thereon and being simultaneously excited by said armature winding.

12. An ignition apparatus for delivering 110 a plurality of sparks simultaneously, including a movable winding with means for generating and controlling a current therein, a plurality of stationary coil structures with at least one winding on each, said movable 115 and stationary windings having independent magnetic circuits, said stationary coil structure windings being excited and controlled by the current from the movable winding and said controlling means.

13. An ignition apparatus for delivering 120 a plurality of sparks simultaneously, including, a winding having a magnetic circuit with means for generating at intervals current in said winding, a plurality of coil 125 structures each having a magnetic circuit independent of the other and of the magnetic circuit of the first mentioned windings, each of said coil structures having at least one winding thereon and being excited by 130 the current generated in said winding.

14. An ignition apparatus for delivering a plurality of sparks simultaneously, including, a winding having a magnetic circuit with means for generating at intervals current in said winding, a plurality of coil structures each having a magnetic circuit independent of the magnetic circuit of the

first mentioned winding, said coil structures having on each at least one winding and being excited by the current generated in the said first mentioned winding.

In testimony whereof, I affix my signature.

EDWARD B. NOWOSIELSKI.
